DESIGN FOR A COMB

Berta Festner, Chandler, Ariz.

Application August 29, 1936, Serial No. 64,634

Term of patent 3½ years

To all whom it may concern:

Be it known that I, Berta Festner, a citizen of the United States and a resident of Chandler, in the county of Maricopa, in the State of Arizona, have invented a new, original, and ornamental Design for a Comb, of which the following is a specification, reference being had to the accompanying drawing, forming a part thereof.

I claim:

The ornamental design for a comb, as shown.

BERTA FESTNER.
